UNITED STATES PATENT OFFICE

102,293

DESIGN FOR A SAFETY REFLECTOR BRACKET

Russell B. Smith, Van Wert, Ohio

Application January 30, 1935, Serial No. 55,153

Term of patent 7 years

To all whom it may concern:

Be it known that I, Russell B. Smith, a citizen of the United States of America, residing at city of Van Wert, in the county of Van Wert and State of Ohio, have invented a new, original, and ornamental Design for a Safety Reflector Bracket, of which the following is a specification, reference being had to the accompanying drawing, forming part thereof.

Figure 1 is a front perspective view of the safety reflector bracket, showing my new design; and Figure 2 is a rear perspective view of the same.

I claim:—

The ornamental design for a safety reflector bracket, as shown.

RUSSELL B. SMITH.
